US0D1029040S

(12) United States Design Patent (10) Patent No.: US D1,029,040 S
(45) Date of Patent:  May 28, 2024

(54) DISPLAY SCREEN OR PORTION THEREOF WITH ICON

(71) Applicant: Salesforce, Inc., San Francisco, CA (US)

(72) Inventors: Andrew Mangano, Sunnyvale, CA (US); Stephen Goldberg, Frisco, TX (US); Saurabh Davala, San Francisco, CA (US); Umesh Zope, Fremont, CA (US); Saket Agarwal, San Mateo, CA (US); Abigail Sigler, San Francisco, CA (US)

(73) Assignee: Salesforce, Inc., San Francisco, CA (US)

() Term: 15 Years

(21) Appl. No.: 29/864,393

(22) Filed: May 25, 2022

(51) LOC (14) Cl. 14-04

(52) U.S. Cl.

USPC D14/492; D14/489
